UNITED STATES PATENT OFFICE.

CHARLES R. EDWARDS, OF HOUSTON, TEXAS, ASSIGNOR OF ONE-HALF TO J. O. MACK, OF HARRIS COUNTY, TEXAS.

DEVICE FOR FORMING SCREENS.

1,323,621.

Specification of Letters Patent.

Patented Dec. 2, 1919.

Application filed April 5, 1919. Serial No. 287,911.

To all whom it may concern:

Be it known that I, CHARLES R. EDWARDS, a citizen of the United States, residing at Houston, in the county of Harris and State 5 of Texas, have invented certain new and useful Improvements in Devices for Forming Screens, of which the following is a specification.

This invention relates to new and useful 10 improvements in a device for forming screens, and has particular relation to a mechanism of the character described, specially designed for forming well screens which consist of perforated pipe and screening wire wound thereon.

As is well known to those familiar with the art of well drilling well screens are employed, which usually consist of perforated pipe wrapped with screening wire, the turns 20 of the wire being spaced apart to form slits, which permit the inflow of the fluid. As now commonly constructed, the screening wire is wound spirally on the pipe, and the turns of wire are soldered together at intervals, to prevent the unwinding of the wire, 25 but this method has proved unsatisfactory, inasmuch as the turns of the wire when so secured are easily displaced, and torn from the pipe in the process of letting the screen 30 down into the well. It is one of the objects of this invention to provide a mechanism whereby the wire may be welded onto the pipe, by an electrical process, as the wire is wound on the pipe, so that the screening 35 wire will be virtually formed integrally with the pipe.

Another object of the invention resides in the process of winding and welding screening wire on perforated pipe.

With the above and other objects in view, 40 the invention has particular relation to certain novel features of construction, operation and arrangement of parts, as well as to the novel process employed, all of which 45 are described in this specification and illustrated in the accompanying drawings, wherein:

Figure 1, is a transverse sectional view taken through the screen, showing the electric wiring employed, diagrammatically.

Fig. 2, is a longitudinal sectional view of the screen, mounted on a mandrel in a lathe and showing a fragmentary view of the wire winding machine.

Referring now more particularly to the

drawings wherein like numerals of reference designate similar parts in each of the figures, the numeral 1, refers to a mandrel, which is fixed against rotation in the lathe 2, said mandrel having the projecting lug 60 3, on one side thereof. Mounted for rotation on this mandrel, is the perforated pipe 4, which is secured at one end in the lathe 2, and which is rotated thereby. As this pipe section is rotated, the screening wire 5 65 is wound spirally thereon in the usual manner, the turns of the wire as wound being held in firm contact against the periphery of the pipe by means of the roller 6, in the wire winding machine. The mandrel 1 is 70 mounted to travel lengthwise in the pipe, in unison with the travel of the winding machine and is so adjusted that the lug 3 will be directly opposite the point of contact of the roller with the wire being wound, and 75 the diameter of the pipe is somewhat greater than the diameter of the mandrel, so the lug 3 will form the only point of contact between them. The numeral 7 indicates a transformer from which the electrical conductors 8 and 9, respectively, lead the former being connected to the roller 6 and the latter being connected to the mandrel, said roller and mandrel thus forming electrodes, and an electrical current of low voltage, and of 80 amperage sufficient to fuse the wire and pipe together, is thus completed from the lug 85 3, of the mandrel through the pipe and the wire, at the point where said wire is coming into contact with said pipe as the winding 90 process proceeds. The pipe and wire are raised in temperature at said point sufficiently to fuse and the wire is held against the pipe by the roller 6, with sufficient pressure to cause them to be welded together, 95 the wire in effect becoming integral with said pipe.

In advance of the roller 6, there is a small caster 10, which is supported from the frame of the wire winding machine by means of the 100 brackets 11, and this caster is connected to the conductor 8 through the conductor 12, which is controlled by a variable resistance coil 13. In case the wire 5 should become hotter than the pipe 4, as will often be the 105 case, part of the current may be switched through the conductor 12, directly to the pipe 4, to control the temperatures of the wire and the pipe.

This device and process may also be em- 110

ployed in brazing or soldering the wire to the pipe, as well, as welding the same, as above specified.

What I claim is:

- 5 1. A device for winding and welding wire on a pipe, including a mandrel, whereon the pipe is mounted for rotation, a wire winding roller adapted to wind the wire on the pipe, and electrical conductors connected to said mandrel and roller, respectively.
- 10 2. A device for winding and welding wire on a pipe, to form a screening surface thereon, consisting of a mandrel, whereon the pipe is mounted for rotation, a wire winding device adapted to wind screening wire on said pipe, and to hold the turns of wire as the wind progresses against the outer side of the pipe, said wire winding device also operating to hold the inner side of said pipe
- 15 20 against one side of said mandrel, and electrical current conductors connected to said roller and mandrel, respectively, and through which an electrical current is completed through said mandrel, pipe, and wire, thereby causing the pipe and wire to fuse.
- 25 3. A device for winding and welding screening wire, on a perforated pipe, and including two electrodes, one of which operates against the outer side of the wire
- 30 30 as wound to hold the same against the pipe, and the other of which contacts with the

inner side of said pipe, opposite the first mentioned electrode, and an electrical conductor, connected to the respective electrodes, whereby an electrical current is completed through said pipe and wire to elevate the temperature thereof to the fusing point whereby the wire is welded to the pipe.

4. The process of forming a well screen, consisting in mounting a screen pipe on a mandrel, winding screening wire therearound, through the instrumentality of a wire winding device, which presses against the outer side of a wire and holds the same against the outer side of the pipe as wound, and passing an electrical current from said mandrel through the pipe and wire to said winding device.

5. The process of forming a well screen, consisting in winding a screening wire spirally on perforated pipe, and simultaneously passing an electrical current through the pipe and wire as the latter is wound whereby said wire is welded to said pipe.

In testimony whereof I have signed my name to this specification in the presence of two subscribing witnesses.

CHARLES R. EDWARDS.
